COMBINED WATCH BRACELET AND WATCH

Samuel Fass, Brooklyn, N. Y.

Application March 30, 1950, Serial No. 8,861

Term of patent 3½ years

(Cl. D45—4)

To all whom it may concern:

Be it known that I, Samuel Fass, a citizen of the United States of America, residing in the Borough of Brooklyn, city of New York, county of Kings, and State of New York, have invented a new, original, and ornamental Design for a Combined Watch Bracelet and Watch, of which the following is a specification, reference being had to the accompanying drawing, forming part thereof as shown:

Figure 1 is an elevational view of a combined watch bracelet and watch showing my new design.

Figure 2 is an elevational view as seen from the right of Figure 1.

Figure 3 is a bottom plan view.

Figure 4 is a fragmentary perspective view illustrating the bottom of the clasp element.

Figure 5 is a fragmentary side elevational view illustrating the clasp element in an open position.

The dominant features of the design reside in the portions shown in full lines.

I claim:

The ornamental design for a combined watch bracelet and watch, as shown and described.

SAMUEL FASS.
